UNITED STATES PATENT OFFICE.

MANUEL F. SILVA, OF CENTERVILLE, CALIFORNIA.

SAFETY APPLIANCE FOR ELEVATORS.

1,188,338.

Specification of Letters Patent. Patented June 20, 1916.

Application filed November 22, 1915. Serial No. 62,779.

To all whom it may concern:

Be it known that I, MANUEL F. SILVA, a citizen of the United States, residing at Centerville, in the county of Alameda and State of California, have invented certain new and useful Improvements in Safety Appliances for Elevators; and I do declare the following to be a full, clear, and exact description of the invention, such as will enable others skilled in the art to which it appertains to make and use the same.

This invention relates to improvements in elevators, and particularly to means by which the same may be prevented from dropping to the bottom of the shaft when the supporting cable breaks.

The principal object of the invention is to provide a very simple yet extremely efficient safety attachment which will automatically operate, if for any reason the cable used for raising the elevator becomes broken.

With this general object in view, my invention resides in the novel features of construction, combination, and arrangement of parts which will hereinafter be more particularly described and claimed and shown in the drawings wherein:

Figure 1 is a vertical section through a portion of a building showing an elevator shaft in section with my improved elevator mounted therein, said section being taken substantially on the line 1—1 of Fig. 6; Fig. 2 is a similar view with the cable broken; Fig. 3 is a vertical section taken substantially on line 3—3 of Fig. 6; Fig. 4 is a similar view taken on the line 4—4 of Fig. 1; and Figs. 5 and 6 are transverse sections taken respectively on the lines 5—5 and 6—6 of Fig. 1.

In the accompanying drawings, I have illustrated a portion of a building showing an ordinary elevator shaft 1 in which my improved elevator with its safety appliances is adapted to slide.

My improved elevator comprises broadly three compartments, the ordinary passenger or freight compartment 2, and additional compartments 3 and 4 disposed above and below this main compartment. The exterior construction of the elevator is similar to the ordinary structure employed in similar devices of this character, the compartment 2 being open on one side as shown at 5 to provide a doorway for ingress and egress there-

from, the other compartments, however, being preferably closed on all sides.

The supporting cable 6 by which the elevator is raised is extended through an opening 7 in the top of the compartment 3 and has its lower or inner end attached to a suitable lifting plate 8 which is substantially the size of the interior dimensions of the compartment and is designed to slide therein. The cable 6 is preferably attached to this plate in its central portion by any preferred means. In the present instance, however, I extend the cable 6 through an opening in the central part of the plate 8 and attach said cable to a rod 9 which extends across the lower face of said plate. This arrangement permits an even, steady pull on the plate, even though the cable is attached thereto only at one point. In order to protect the cable 6 where it extends through the top of the compartment 3 and to prevent excessive wear, a tube 10 is provided. This tube is secured by its lower end to the plate 8 and extends upwardly through the opening 7 in the top and surrounds said cable. The plate 8 being free to move in the compartment 3, the same will be lifted upwardly when force is exerted on the cable to pull the same and the elevator upward. When, however, the cable is not supporting the weight of the elevator, the plate 8 is forced downwardly by means of a heavy coiled spring 11 which surrounds the tube 10. The purpose of this construction will hereinafter be more particularly described.

The lowermost compartment 4 has a pair of spaced apart upright bearing plates 12 disposed therein, the plates being preferably arranged parallel to the front of the compartment. These plates 12 have rotatably mounted therein a pair of shafts 13, said shafts being positioned adjacent and parallel to the sides of the elevator and therefore at right angles to the plates 12. The ends of these shafts are extended beyond the plates 13 and receive the safety catches 14 which are adapted to operate to prevent the movement of the elevator when the cable 6 becomes broken. Each of these safety catches 14 is in the form of a substantially triangular flat plate having one of its edges rounded as shown at 15 and provided with gear teeth 16. These plates and the shafts 13 are so arranged that the teeth 16 on the rounded edges 15 thereof intermesh as 110

shown. Two pairs of these intermeshing plates are provided, one pair on the outer side of each of the bearing plates 12. The corners of the plates opposite their rounded portion 15 are adapted to project beyond the sides of the elevator when the cable 6 breaks, said corner being provided with spurs 17 adapted to bite into the walls of the elevator shaft and reliably hold said elevator in stationary position until the cable can be repaired. When the elevator is operated, however, the safety catches are disposed in inactive position, and are only moved therefrom by the means now to be described.

The bearing plates 12 in addition to providing bearings for the shafts 13, also have arcuate slots 18 formed therein through which extend operating rods 19, one of these rods connecting each pair of plates on each of the shafts 13. It will be seen that as long as one or both of these operating rods are held in its or their uppermost position, the safety catches will be held in inactive position as shown in Fig. 1. As the teeth of the safety catches intermesh, it is only necessary to move one of the operating rods in order that both sets of safety catches may be operated. They are thrown into their operative position when the operating rods connecting them are moved downwardly through any cause, thus throwing the spurred corners 17 into engagement with the walls of the elevator shaft.

In order that the rods 19 may be held in their uppermost position, I connect the same by means of a lifting rod 20 to the lifting plate 8. Thus as the plate 8 is raised by the cable 6, the operating rods 19 will also be raised. A yoke 21 is used as a means of lifting both of the operating rods simultaneously, said yoke being connected in any suitable manner to the lower end of the lifting rod 20. Furthermore, the rods 19 are surrounded by the rollers 22 in order that any friction occasioned by their being lifted will be overcome. When the cable 6 breaks at any point, the weight of the elevator will be removed from the plate 8, thus allowing the spring 11 to force the same downwardly, which on its downward movement will also cause the lifting rod 20 to force the operating rods 19 downwardly, and causing the plates forming the safety catches to be rotated so that their spurred corners will be thrown into active position. This operation takes place very quickly and automatically whenever the cable breaks, and the elevator will drop only a short distance before the spurs 17 forcibly engage the walls of the elevator shaft. These spurs 17 may be either formed integrally with the plates constituting the safety catches, or they may be formed on separate wear members 23 which cover the outer edges of each

of the plates. As the lifting rod 20 necessarily extends upwardly through the passenger compartment 2, I provide a suitable housing therefor in the form of a tube 24.

From the foregoing description, it will be seen that I have invented an extremely simple yet positive means for stopping an elevator at any point in its shaft when the supporting cable therefor becomes broken.

While I have described the elements best adapted to perform the functions of my invention, it is obvious that various changes may be made in the form and proportion thereof without departing from or sacrificing any of the principles of the invention.

I claim:

1. The combination with an elevator shaft; of an elevator slideable therein, a lifting plate in said elevator adapted to support the weight thereof, a cable attached to said plate, a shaft rotatably mounted transversely of said elevator, normally inactive safety catches on the ends thereof, an operating rod connecting said catches, a lifting rod connecting said plate with the first mentioned rod, means for forcing said operating rod downwardly, whereby when said cable breaks, the safety catches will be forced outwardly into engagement with the walls of said elevator shaft.

2. The combination with an elevator shaft; of an elevator slideable therein, a lifting plate in said elevator adapted to support the weight thereof, a cable attached to said plate, a shaft rotatably mounted transversely of said elevator, normally inactive safety catches on the ends thereof, an operating rod connecting said catches, a yoke on said rod, a lifting rod connecting said plate and the yoke, a spring placed above said plate for forcing the same downwardly, whereby when said cable breaks, the safety catches will be forced outwardly into engagement with the walls of said elevator shaft.

3. The combination with an elevator shaft; of an elevator slideable therein, a supporting cable for lifting said elevator, a pair of shafts extending transversely of said elevator and rotatably mounted therein, safety catches on the ends of said shafts in the form of substantially triangular plates having one edge thereof rounded, intermeshing gear teeth on said rounded edges, operating rods connecting said plates, the corners of said plates opposite the front edges forming spurs adapted to be thrown into engagement with the walls of the elevator shafts when the supporting cable breaks.

4. The combination with an elevator shaft; of an elevator slideable therein, a lifting plate in said elevator adapted to support the weight thereof, a cable attached to said plate, a pair of shafts extending transversely of said elevator and rotatably mounted therein, safety catches on the ends of said

shafts each having one edge thereof rounded, intermeshing gear teeth on said rounded, intermeshing gear teeth on said rounded edges, the corners of said plates opposite said 5 rounded edges forming spurs, operating rods connecting said plates, a lifting rod attached by its opposite ends to said plate and the operating rods, and means for forcing said plate downwardly, whereby when said cable 10 breaks, the safety catches will be forced outwardly into engagement with the walls of said elevator shaft.

5. The combination with an elevator shaft; of an elevator slidably therein, a supporting cable for lifting said elevator, a pair 15 of upright spaced apart bearing plates, a pair of shafts rotatably mounted therein, the ends thereof projecting beyond said plates, safety catches on said projecting ends

and adapted to rotate therewith, said catches having their adjacent edges rounded, intermeshing gear teeth on said rounded edges, said bearing plates also having arcuate slots therein, operating rods extending through 20 said slots and connecting the safety catches, a connection between said rods and the cable, and means for forcing said rods downwardly, whereby when said cable breaks, 25 the safety catches will be forced outwardly into engagement with the walls of said elevator shaft. 30

In testimony whereof I have hereunto set my hand in presence of two subscribing witnesses.

MANUEL F. SILVA.
